CLAIM

The ornamental design for a flashlight holder clamp assembly, as shown and described.

DESCRIPTION

FIG. 1 is a front perspective view of a flashlight holder clamp assembly showing our new design;

FIG. 2 is a front elevational view thereof on an enlarged scale;

FIG. 3 is a rear elevational view thereof on an enlarged scale;

FIG. 4 is a side elevational view on an enlarged scale of either side, said sides being identical;

FIG. 5 is a top plan view thereof on an enlarged scale; and,

FIG. 6 is a bottom plan view thereof on an enlarged scale.

FIG. 1.

FIG. 5.

FIG. 6.

FIG. 2.

FIG. 3.

FIG. 4.
